UNITED STATES PATENT OFFICE.

DAVID WILLIAM RIPLEY, OF FRESNO, CALIFORNIA.

BOX-NAILING TABLE.

Application filed September 9, 1920. Serial No. 409,250.

To all whom it may concern:

Be it known that I, DAVID WILLIAM RIPLEY, a citizen of the United States, and resident of Fresno, in the county of Fresno and State of California, have invented a new and useful Improvement in Box-Nailing Tables, of which the following is a specification.

My invention relates to an improved box nailing table and more particularly to the elevating means therefor. It is well known that to reinforce boxes containing merchandise, and sometimes to bind two or more boxes together in one package, it is a common practice to nail a wire, a metal strip, or tape around the ends of the box, or a plurality of boxes in one pile. While ordinary box making machines are adapted to nail the boxes together and can be used to nail the tape thereon, one of the difficulties not overcome heretofore was the fact that such box making machines are adapted to operate only on boxes of a uniform size, and irregularity in the height of the box would cause the nails to be driven into the wood too far, or not far enough. The object of my invention is an improvement in a box making machine which will be automatically responsive in adjustment to the height of the box being nailed, so that the elevating device for the boxes will be responsive to the differences in height of the boxes, always raising them so that the upper surface of the box is at a predetermined height, and adjacent to the nail boxes of the machine.

To accomplish this object, and other objects hereinafter set forth, I have constructed a machine a description of which is set forth in the specification herein, and illustrated on the accompanying drawing, in which Figure 1 is a front partial view of the machine. Figure 2 is a side view of the same portion of the machine as is shown in Figure 1. Figure 3 is a plan view of the hydraulic press and valves and pipes. Figure 4 shows a centrifugal pump which is one means that can be used for supplying hydraulic pressure. Figure 5 is a side view, partly in section, of the cradle for holding the boxes for nailing and turning, and shows the means for turning the box around.

In said drawings 2 is the base on which the machine stands. 3 and 3^a are two upright main posts attached to base 2. The faces 3^{aa} on posts 3 and 3^a are on a common plane and form vertical slideways. 7 is a bracket having braces 7^b and 7^c and a top

7^a formed integral therewith. Bracket 7 is adapted to slide vertically on slideways 3^{aa}. The slideway 3^{aa} extends slightly beyond the face of posts 3 and 3^a. 7^d is a cleat bolted to bracket 7^c to hold it against slideway 3^{aa}. The upper surface of top 7^a should be a horizontal plane. 8 is a screw, and 8^a is a screw base having a threaded hole therein to receive screw 8. Screw base 8^a is attached to base 2. The upper end of screw 8 rests in a socket 8^c. It will be noted that by moving screw 8 the bracket can be raised or lowered. To rotate screw 8 I have attached a gear 8^b thereon which is turned by an intermediate gear 8^c, which receives its movement from a gear 8^d to be turned by a crank 8^e. The purpose of the screw designated 8 is to adjust the height of the bracket top 7^a. 10 is a cradle for holding the boxes to be nailed. It consists of two circular frames 10^a and 10^b which are attached together a spaced distance apart, so the frames are concentric, by means of four tie rods 10^c, 10^d, 10^e and 10^f. 9 is a cradle holder, and consists of slideways 9^a and 9^b adapted to engage the peripheries of circular frames 10^b and 10^a and to permit said cradle 10 to slide vertically and to rotate within the cradle holder, but which will not permit the cradle to have a horizontal movement. The interior of the cradle is formed rectangular, with rigid supports 10^g connecting the circular frames on lines of segments of the circular frames. The size and relative shape of the rectangular opening should be adapted to receive boxes to be strapped so that the ends of the box extend beyond the cradle.

Means for rotating the cradle consist of an auxiliary ring 11 of such diameter that it will easily rotate around the four tie rods 10^c, 10^d, 10^e and 10^f when it is placed concentric with cradle rings 10^a and 10^b. 11^a is a handle extending radially therefrom. 11^b is a dog pivoted to auxiliary ring 11. 11^c designates guide pins, extending radially in pairs from the tie rods 10^c, 10^d, 10^e and 10^f, said pins forming an annular path in which the auxiliary ring 11 can travel. 11^d is a stop attached to cradle support 9 in line with the travel of handle 11^a, its purpose being to stop the rotation of the cradle at a point where one of the faces of the box is on a horizontal plane. In raising the handle 11^a it will be noted that the dog will drag over one of the rods 10^c, 10^d, 10^e, or 10^f, and that

by reversing the movement of the handle 11^a the dog 11^b will engage with one of the rods 10^c, 10^d, 10^e or 10^f and that the cradle will be turned on its axis, together with the 5 contents of the cradle, which may be two boxes 13^a and 13^b as shown. 16 is the main support for a plurality of nail boxes 12^b, 12^c, 12^d and 12^e. The nail boxes 12^b, 12^c, 12^d and 12^e are placed in a horizontal line beyond 10 the ends of the cradle and are adapted to be adjusted so that the nail boxes will be on line with the ends of the box. In a separate application Serial No. 434,592, filed January 3, 1921, is disclosed one of the means which 15 may be used for feeding and driving the nails into the box. The nail boxes 12^b, 12^c, 12^d and 12^e should be spaced far enough from bracket top 7^a so that the boxes 13^a and 13^b when within the cradle can be turned 20 around in the space between said top and the nail boxes. 14 is a metal tape which is brought over a guide 14^a into a path directly under the nail boxes and over the ends of the box for the purpose of nailing it thereon. 25 It will be noted that normally the top surface of the box 13^a, (when in cradle 10) is below the nail boxes. For the purpose of elevating the box so that it is adjacent to said nail boxes and held rigidly in said position while being nailed, I have provided two auxiliary slideways 15^a and 15^b which are attached to base 2 and which extend in a vertical line which would intercept an extended axis of the cradle and just beyond 30 the two ends of the cradle. 15^c and 15^d are slides adapted to slide in slideways 15^a and 15^b. These slides extend through bracket top 7^a and terminate at the top with cross supports 15^e and 15^f. The cross supports 15^e 35 and 15^f are in line with the bottom of the ends of the box 13^b. 15^g is a cross bar joining the slides 15^c and 15^d. These slides are operated by means of hydraulic pressure consisting of a cylinder 17, a piston therein 40 17^a, which is connected with cross bar 15^g by means of piston stem 17^{aa}. 17^c is a three-way valve. 17^d is a supply tank. 17^e is a centrifugal pump which draws the liquid it pumps from supply tank 17^d. 17^f is a lead 45 from pump 17^e to the three-way valve and it also connects with lead 17^{dd} to tank 17^d. 17^g is a lead from the three-way valve to the discharge opening of pump 17^e. 17^h is a lead from the three-way valve to cylinder 17. 50 17ⁱ is the valve. 17^k is a rod attached to the valve plunger for operating it. 17^l is a spring which normally keeps the valve in a position so the lead from the outlet of the pump to the cylinder is normally opened. 17^m is a 55 check valve permitting liquid to flow from the pump but not toward it. It will be noted that the valve rod 17^k is placed in a position so that the end will engage with handle 11^a and the valve 17ⁱ can be depressed by pushing down on the handle 11^a. 11^f is a guide for 60 rod 17^k. By this means it will be noted that boxes 13^a and 13^b can be inserted in the cradle, the hydraulic force can be turned on and the slides 15^c and 15^d will move upward lifting the box and the cradle to a level so 70 that the top surface of the box will be pressed against the nail boxes and the check valve will hold the fluid in the cylinder 17 and hold the box rigid for nailing. When the nailing of the box on the uppermost side 75 is completed, the valve is operated to release the hydraulic pressure, the cradle is turned one quarter around thus presenting another side uppermost, and the hydraulic pressure is again made operative to bring the box in 80 position adjacent to the nail boxes and this is repeated until the four sides of the box are in turn placed uppermost and adjacent to the nail boxes. By use of the hydraulic pressure for raising the boxes into position 85 for nailing, the lack of uniformity in the height of the boxes is overcome as each face placed uppermost is pressed against the nail boxes by uniform hydraulic pressure. 90 The nailing device is described in a separate application above referred to.

Having described my invention I claim Letters Patent:

1. In a box making machine the combination of a box holder rotatable around a horizontal axial line and positioned directly under a nail box, a vertical slideway in which the box holder is adapted to slide, a table positioned directly under the box holder and vertically slidable within limits which permit the box holder to rotate, and permits the table to be moved adjacent to the box within the box holder in any position said box holder may be within the box holder slideway. 95
2. In a box making machine the combination of a box holder rotatable around a horizontal axial line and positioned directly under a nail box, stop means for locking the rotation thereof on each quarter turn, a vertical slideway adapted to receive the box holder for slidable movement therein, a table vertically slidable and positioned directly under the box holder and adapted for engagement therewith, and means for elevating and lowering said table, substantially as described. 110
3. A box nailing table consisting of a box holder rotatable around a horizontal axial line, rings surrounding the box holder and attached thereto having their centers registering with said horizontal axial line, vertical slideways for the peripheries of the rings, means for rotating the box holder within the slideways, and independent means for sliding the rings within the slideways, substantially as described. 120
4. In a box making machine having means for driving nails, a nail box, a box holder rotatable about a horizontal axial line posi- 130

- tioned under the nail box, a vertical slide-way for the box holder, means for raising the box holder so that the upper surface of the box within the box holder will be on the same plane as the under surface of the nail box consisting of a slideway and a slide therein terminating at the top with a platform arranged to come in contact with the under side of the box when the slide is moved upwards, means for moving said slide upwards consisting of a hydraulic cylinder, a piston within the cylinder, hydraulic pressure for moving the piston upwards, and a piston stem attached at one end to the piston and at the other to the side, and adapted to move the slide upward as the cylinder moves upward, and a check valve adapted to hold the pressure against said slide until released by manual means, substantially as described.
- 5 10 15 20 25 30
5. In a box making machine having means for driving nails, a nail box, a box holder rotatable about a horizontal axial line positioned under the nail box, a vertical slide-way for the box holder, means for raising the box holder so that the upper surface of the box within the box holder will be on the same plane as the under surface of the nail box consisting of a slideway and a slide therein terminating at the top with a platform arranged to come in contact with the under side of the box when the slide is moved upwards, means for moving said slide upwards consisting of a hydraulic

cylinder, a piston within the cylinder, hydraulic pressure for moving the piston upwards, a piston stem attached at one end to the piston and at the other to the side, and adapted to move the slide upward as the cylinder moves upward, and a check valve adapted to hold the pressure against said slide until released by manual means, substantially as described.

40

6. In a box making machine having means for driving nails, a nail box, a cradle consisting of two circular rings attached together at four spaced points adjacent the peripheries of the rings, rectangular frames within said rings adapted to hold a box, a support for said cradle constructed and arranged to permit the cradle to be rotated within the support and slid relative thereto, means for rotating the cradle in said support, means for sliding the cradle in said support consisting of a cylinder, a push rod connected with the cylinder and terminating at its other end in a support adapted to engage a box in the rectangular frames, means for raising the piston in the cylinder by hydraulic pressure, a check valve adapted to hold the pressure in the cylinder and means for releasing the pressure in the cylinder.
